(57) **CLAIM**

The ornamental design for the scaffold wrench holster with retractor, as shown and described.

DESCRIPTION

FIG. 1 is a perspective view of our new scaffold wrench holster with retractor showing our new design;

FIG. 2 is a front elevational view thereof;

FIG. 3 is a rear elevational view thereof;

FIG. 4 is a right side elevational view thereof, the left side being a mirror image thereof;

FIG. 5 is a top plan view thereof; and,

FIG. 6 is a bottom plan view thereof.

The scaffold wrench depicts environmental structure that forms no part of the claimed design.
